HOISTING APPARATUS

Alvin Gaskin, Russell Springs, Ky.; Morris Montgomery, Liberty, Ky., executor of said Alvin Gaskin, deceased

Application June 23, 1952, Serial No. 295,068

4 Claims. (Cl. 254—140)

1

This invention relates to hoisting apparatus and more particularly to hoisting apparatus in which the load being hoisted when it reaches a desired hoisted position may be rotated through an angle of 90° and moved away from the original hoisting axis before being lowered to rest upon suitable supports.

The hoisting apparatus of the present invention is suitable for many uses and has particular application for use in the hoisting and locating of tobacco hangers in tobacco drying barns. The invention will be hereinafter described with particular reference to this use but it is to be understood that the invention is not so limited.

Heretofore various hoisting apparatus have been suggested for hoisting tobacco hangers, among other uses, but none of these have provided means for rotating the hanger with its load of tobacco leaves through a 90° angle to place the same at right angles to the direction of the supporting rafters of a barn and at the same time to move the tobacco hanger and its load away from the original axis of hoist so that when the hanger is lowered it will be appropriately placed and spaced on the supporting rafters.

It is accordingly an object of the present invention to provide novel hoisting apparatus by which the load being hoisted may be rotated through an angle of 90° and at the same time displaced laterally from the original axis of hoist to appropriately position the load upon supports when the load is lowered.

Another object is to provide such hoisting apparatus in which the load to be hoisted may be elevated between series of supporting beams and in a desired position rotated through an angle of 90° and displaced laterally so the load will rest upon desired supporting beams when lowered.

Another object is to provide such hoisting apparatus which is of simple construction, easy to manufacture, and easily handled by one man.

Another object is to provide such novel hoisting apparatus which is light weight and easily positioned and moved during the operation of filling a barn such as a tobacco drying barn.

Other and further objects of the present invention will appear from the following description.

The hoisting apparatus of the present invention is capable of various mechanical embodiments one of which is shown in the accompanying drawings and is described hereinafter for purposes of illustrating the same. This illustrative embodiment of the present invention should in no way be construed as defining or limiting the same and reference should be had to the ap-

2

pended claims to determine the scope of this invention.

In the accompanying drawings, in which like reference characters indicate like parts, Fig. 1 is a view of an illustrative embodiment of the hoisting apparatus of the present invention showing its use for hoisting tobacco hangers with the hanger arranged lengthwise so as to pass between supporting beams in a tobacco barn;

10 Fig. 2 is a view of the embodiment of Fig. 1 showing the apparatus of the present invention with a tobacco hanger in hoisted position and partially rotated about the hoisting axis and partially displaced laterally therefrom and rotating toward its position of rest across supporting beams in a tobacco barn; and

15 Fig. 3 is a view of the apparatus of Fig. 1 with the tobacco hanger rotated through an angle of 90° from the position shown in Fig. 1, laterally displaced from the hoisting axis of Fig. 1 and positioned for lowering onto the supporting beams of the barn.

20 Referring now to the several figures, suitable supporting beams for tobacco hangers such as are found in a tobacco barn are generally indicated at 10. These beams 10 are arranged in parallel relationship and are laterally and vertically spaced in conventional manner as is well known to the art. In the embodiment of the hoisting apparatus of the present invention as disclosed in these figures 11 represents a cross beam, rounded at its ends as at 12 and 13 and of suitable length to rest upon adjacent parallel beams 10. The ends 12 and 13 are rounded so that beam 11 is free to rotate upon the supporting beams 10. A cross member 14 is secured midway between ends 12 and 13 and supports a suitable pulley 15 at one end thereof. A hoisting line 16 passes through pulley 15 and is provided with a hoisting frame 17 at one end. The other end of rope 16 passes through eye 18 secured to frame 17. Frame 17 is provided with turned parallel ends 19 and 20 to receive a suitable tobacco hanger 21.

25 An arm 22 is mounted for universal motion at 23 upon beam 11. A second arm is universally connected at 25 to the free end of arm 22. The other end of arm 24 is secured to a circular drum 26. Drum 26 rotates about a pivot 27 which passes through a fork 28, which embraces arm 24, and fork 28 terminates in stem 29 which is mounted for rotation in bracket 30 which is secured by screws 31 to a side of beam 11. A bar 32 having a ring end 33 is loosely mounted 30 on eye 34 which is secured to the end of cross

member 14 opposite the pulley 15. A second link 35 is loosely connected to link 32 at 36 and in turn is loosely connected at 37 to a rod 38 carrying a stop 39. A guide 40 receives rod 38 and is secured to arm 24. A guide rope 40 is connected at 41 to rod 38. An extensible spring loaded link 42 is secured to frame 17 and terminates in an eye 43 embracing guide rope 40. A connecting rod 44 may be rigidly secured to arm 22 and loosely connected to the flexible connection 36.

Suitable resilient means such as the spring 45 embraces the outer circumference of drum 26 and is secured at one end thereto as at 46 and is secured at its other end as at 47 to beam 11.

In using the embodiment of the present invention as described and particularly when using it for the hoisting and placing of tobacco hangers the beam 11 is suitably placed upon supporting rafters 10 as shown in Fig. 1 and a hanger 21 supporting tobacco leaves in known manner is placed upon ends 19 and 20 of frame 17. Hoisting rope 16 is then hauled to raised frame 17 and hanger 21, eye 18 riding over rope 16 to prevent swinging of hanger 17 and to keep the long axis of hanger 21 parallel to the rafters 10. When frame 17 has reached its elevated position adjacent pulley 15 guide rope 40 is hauled. Hauling on guide rope 40 starts frame 17 rotating through the agency of extensible connector 42 and at the same time engages stop 39 against guide 40 and rotates arms 22 and 24 about their respective pivots 23 and 27, the motion of arm 24 tensioning spring 45. An intermediate position of the hoisting apparatus of the present invention with frame 17 and tobacco hanger 21 partially rotated about the axis of hoisting rope 16 is shown in Fig. 2.

Further hauling upon guide rope 40 rotates arms 22 and 24 to their extreme positions at which links 32 and 35 prevent further motion of arms 22 and 24 and thereafter further hauling on rope 40 rotates cross member 14 into a horizontal position displacing frame 17 laterally away from the original hauling axis and completes a 90° rotation of frame 17 and hanger 21. Thereafter hauling rope 16 can be slackened away and hanger 21 is lowered into position upon the supporting rafters 10. This last position of the hoisting apparatus and hanger 21 is shown in Fig. 3 with the tobacco hanger 21 in lowered position shown by arrows and dotted lines.

The extensible feature of connector 43 permits lateral displacement of frame 17 and hanger 21 while at the same time holding and swinging them through the desired ninety degrees of rotation.

After tobacco hanger 21 is in place upon the rafters 10 hoisting rope 16 is further slackened off until frame 17 disengages hanger 21. Thereafter guide rope 40 is slackened off allowing cross member 14 to rotate beam 11 so that pulley 15 moves to its lowest position as shown in Fig. 1. At the same time spring 45 is rotating drum 26 and arm 24 toward the position shown in Fig. 1 carrying arm 22 and associated linkage with it. Extensible member 42 is contracted to its initial position and frame 17 swings through a 90° angle to a position in which its plane is parallel to the long axes of the rafters 10. Frame 17 may now pass downwardly through the parallel rafters 10 without engaging them and hoisting rope 16 is further slackened off for this purpose.

It should be particularly noted that when the hoisting apparatus of the present invention is in

the position shown in Fig. 1 all of its elements are in substantially the same plane so that the hoisting apparatus may be easily hoisted upwardly between the parallel rafters 10 and can be moved about within the restricted openings found in conventional tobacco barns without difficulty. Such would not be the case if the arms 22 and 24 with associated linkages were affixed in the position shown in Fig. 3 although if so fixed in position the operation of the apparatus would be substantially as described above. The motion provided arms 22 and 24 by the guide rope 40 is a desirable feature of the present invention in view of the compactness thereby provided for the apparatus. However it is within the scope of the present invention to fix the arms 22 and 24 in somewhat the position shown in Fig. 3 although thereby losing the advantages of compactness.

It should now be apparent to those skilled in the art that changes in or modifications to the above described illustrative embodiment of the present invention can be made without departing from the inventive concept thereof even though such departures might reduce the compactness of the apparatus or its ease of operation in restricted spaces. For example, instead of employing arms 22 and 24 with associated linkages the guide rope 40 could be connected to an arm rigid with cross member 14 and extending at right angles thereto adjacent the end of arm 14 and opposite the pulley 15. Such a structure would, however, lose the compactness of the described embodiment of the present apparatus and would limit the utility of the same in and about restricted spaces. In view of the changes possible to the described structure of the present invention reference should be had to the appended claims to determine the scope of the same.

What is claimed is:

1. In hoisting apparatus including pairs of spaced parallel supporting rafters, a beam rotatably supported across a pair of rafters, a cross member secured to said beam, a pulley rotatably mounted on one end of said cross member, a hoisting rope passing through said pulley, a hoisting frame carried by said hoisting rope, an eye on said frame to receive said hoisting rope, a guide rope, extensible means secured to said frame at one end and receiving said guide rope at its other end, and linkage means connecting said guide rope to the end of said cross member opposite said pulley, said linkage means including an arm universally mounted at one end on said beam, a second arm universally connected to the other end of said first arm and universally connected to said beam at its other end and resilient means for rotating said arms into the plane of said beam, said guide rope connecting adjacent the universal connection between said arms and linked to the end of said cross member opposite said pulley.

2. Hoisting apparatus as described in claim 1 including a guide way secured to one of said arms adjacent the universal connection between said arms, a bar slidably mounted in said guide way linkage connecting one end of said bar to the end of said cross member opposite said pulley, said guide rope being connected to the other end of said bar.

3. In hoisting apparatus including pairs of spaced parallel supporting rafters, a beam rotatably supported across a pair of rafters, a cross member secured to said beam and extending on opposite sides thereof, a pulley rotatably mount-

ed on one end of said cross member, a hoisting rope passing through said pulley, a hoisting frame carried by said hoisting rope, an eye on said frame to receive said hoisting rope, a guide rope, extensible means secured to said frame and receiving said guide rope, a pair of arms connected for universal movement at adjacent ends and connected at their other ends for universal movement to said beam, one of said last named universal connections including resilient means for rotating said arms into the plane of said beam and means for connecting said guide rope to said arms and to the end of said cross member spaced from said pulley.

4. Hoisting apparatus as described in claim 3 in which said resilient means includes a drum secured to one of said arms, a fork carrying said drum for rotation, means for rotatably securing said fork to said beam, and spring means secured to and passing around said drum and secured to said beam.
